UNITED STATES PATENT OFFICE.

JOHN M. KERR, OF LOUISVILLE, KENTUCKY, ASSIGNOR OF ONE-HALF TO JOSEPH WERNERT.

MAIL-BAG CATCHING AND DELIVERY APPARATUS.

Application filed June 27, 1921. Serial No. 480,736.

To all whom it may concern:

Be it known that I, JOHN M. KERR, a citizen of the United States, residing at Louisville, in the county of Jefferson and State of Kentucky, have invented new and useful Improvements in Mail-Bag Catching and Delivery Apparatus, of which the following is a specification.

This invention relates to improvements 10 in mail receiving and delivering apparatus and has for an object the provision of an apparatus by means of which mail matter may be delivered from and received by a train while the latter is in motion.

15 Another object is the provision of an apparatus of the above type in which the mail delivered at a station is received within an enclosed station receiving device, which, in addition to being protected from the elements, also acts to prevent the mail from being handled by unauthorized persons.

20 Another object of the invention is the provision of a mail handling apparatus in which the train carried delivering mechanism is housed beneath the same so as to prevent unnecessary crowding and danger of accident to occupants of the car, the position of the apparatus being such as not to extend beyond the sides of the car, so that danger of 25 contact with adjacent objects is obviated.

30 A further object of the invention is the provision of an apparatus of the above character, which is simple of construction, positive in operation and which will handle the mail in a manner to minimize injury thereto.

35 With the above and other objects in view, the invention further includes the following novel features and details of construction, to be hereinafter more fully described, illustrated in the accompanying drawings and 40 pointed out in the appended claims.

In the drawings:—

45 Figure 1 is a side elevation of a fragmentary portion of a mail car showing the application of the invention.

Figure 2 is a fragmentary view of a portion of the car, parts being broken away and part of the car delivering device being shown in plan and other parts in section, the view 50 also showing the station receiving device with its housing in section.

Figure 3 is a view similar to Figure 2 showing the apparatus in position for deliver-

ing mail from the car delivering device into the station receiving device. 55

Figure 4 is an enlarged sectional view on the line 4—4 of Figure 1.

Referring to the drawings in detail, wherein like characters of reference denote corresponding parts, the apparatus includes a 60 car delivering device which is indicated generally at A and a station receiving device indicated generally at B, by means of which mail matter may be delivered from the car to a station along the line of travel. The invention further includes a car receiving device which is indicated generally at C and a station delivering device, the latter being indicated at D. This provides means whereby mail matter may be delivered from a station 65 into a passing car. 70

Referring particularly to the devices A and B, the former includes a hopper 10 which extends through the floor of the car and is provided on its top with a cover 11, 75 which is normally closed. This hopper extends only a short distance above the floor of the car and contains means whereby the mail matter may be guided into an ejecting frame 12 which is located beneath the bottom of the 80 car. This frame may be of any suitable or desired shape, but is shown as rectangular and is housed within a pocket 13 which is formed within a casing or frame 14. This ejecting frame 12 is hingedly secured at one 85 corner as indicated at 15 and is movable out of and into the pocket 13 being guided by the top and bottom walls of the housing or frame 14. The bottom wall forms a bottom for the ejecting frame 12. The pocket 13 is 90 of triangular shape and its rear wall 16 forms a stop to limit the inward movement of the frame 12.

Pivotedly secured to the corner of the pocket opposite the hinge 15, as indicated at 95 17, is one end of a rod 18. The opposite end of this rod is pivotally secured as shown at 19 to the outer end of a block 20, the latter being hinged at one end as shown at 21 to a stationary member or block 22. This block 100 acts to return and hold the ejecting frame 12 within the pocket and for this purpose has connected thereto one end of a spring 23, whose opposite end is connected to a stationary member as shown at 24. 105

In order to cushion the inward movement

of the frame, the rod 18 has connected thereto one end of a rod 25 which is controlled by a piston 26 which is movable within a cylinder 27.

5 The station receiving device B includes a housing 28 and located within this housing is a sectional ejecting arm. This arm includes an inner section 29 and an outer section 30, these sections being hingedly secured together as shown at 31. The inner end of the inner section 29 is pivotally mounted as shown at 32 while the outer end of the outer section 30 is arranged to engage a U-shaped member or loop 33 which extends from one corner of the ejecting frame 12. This end of the section 30 is also provided with a notch 34 and when the arm engages the loop 33, the frame 12 is moved out of the pocket upon its hinge 15, while 10 the ejecting arm sections move upon their pivot and hinge so that the loop 33 engages in the notch 34 and the frame 12 is pulled out of the pocket a sufficient distance to permit the mail matter to fall through the 15 frame into a receiving compartment 35, provided in the housing 28. This movement of the sections 29 and 30 and of the ejecting member is resisted by means of springs 36 and 37 which are connected to the respective 20 sections and act to return the arm to its normal position, the return movement being limited by a cushioned stop in the form of a spring 38.

After the mail matter has been deposited 25 within the hopper 10, it will fall into the ejecting frame 12, when the latter is engaged by the ejecting arm of the station receiving device B, the said frame will be withdrawn from the pocket and the mail matter deposited 30 in the receiving compartment 35 as just described. Access to the compartment 35 is had through a door 39, which may be supplied with a suitable lock 40 so as to prevent the mail being tampered with by unauthorized persons.

The station delivering device D and the car receiving device C are substantially the same as that described in connection with the devices A and B. The device D is herein 35 shown as mounted upon the top of the casing which houses the station receiving device B, a suitable supporting structure 41 being provided for this purpose. The device D is located within a housing 42 which is provided with a receiving hopper 43 extending above the top and communicating with the interior. The mail matter may thus be deposited within this hopper and received within a pivotally mounted ejecting frame 44 which is similar to the frame 12 previously described and which is operated by the receiving device C. The frame 44 operates within a pocket 45 provided in the housing 42 and located within this housing is a returning block 46 which is con-

nected to the frame 44 by a rod 47 and which is actuated by a spring 48. The cushioning means 49 similar to the means previously described is connected with the rod 47 by a rod 50.

70 The receiving device C comprises a sectional arm 51 which is constructed in a manner similar to the sectional ejecting arm previously described, and which is adapted to engage a loop 52 extending from the 75 frame 44. The arm 51 is located within a housing 53 which is carried by the mail car and this action is resisted by springs 54 and 55, which also serve to return the arm to its 80 normal position. The return of this arm is cushioned by a spring 56. The mail matter ejected from the frame 44 is received within a compartment 57 provided in the housing 53 and the latter is movable transversely of the 85 car. For this purpose there is provided a track 58 which is arranged within the upper portion of the car and when in receiving position the device C projects through an opening 59 provided in the side of the car. When at the limit of its inward movement 90 the casing of the device C acts to close this opening, while the outward movement of this casing is limited by stops 60 which are carried by each end of the casing and which engage suitable stops 61 provided at 95 each end of the opening 59.

The invention is susceptible of various changes in its form, proportions and minor details of construction and the right is herein reserved to make such changes as properly fall within the scope of the appended 100 claims.

Having described the invention what is claimed is:

1. An apparatus of the class described 105 embodying a car delivery device, said device comprising a pocket located upon the outside of the car, a hopper communicating with the interior of the pocket, a horizontally movable pivoted ejecting frame 110 movable out of and into the pocket and means whereby the ejecting frame may be operated.

2. An apparatus of the class described 115 embodying a car delivery device, said device comprising a pocket located upon the outside of the car, a hopper communicating with the interior of the pocket, a horizontally swinging spring returned ejecting frame located within and movable out of the 120 pocket, means for moving the frame outward and means for cushioning the return movement of the frame.

3. An apparatus of the class described 125 embodying a car delivery device, said device comprising a pocket located upon the outside of the car, a hopper communicating with the interior of the pocket, a spring returned ejecting frame located within and movable out of the pocket, means for mov- 130

ing the frame outward and a pneumatic cushioning element for retarding the return movement of the frame.

4. An apparatus of the class described embodying a car delivery device, a horizontally arranged pocket included in said device, a horizontally movable ejecting frame open at its top and bottom and normally housed within the pocket, means located adjacent the car track for moving the ejecting frame outward from the pocket and means for returning the ejecting frame to normal position.

5. An apparatus of the class described embodying a car delivery device, said device comprising a pocket located upon the outside of the car, a hopper communicating with the interior of the pocket, a pivoted ejecting frame movable out of and into the pocket, a rod having one end secured to the ejecting frame, a spring actuated pivotally mounted member secured to the other end of the rod and moving the frame

inward, a cushioning element connected to the rod and means located adjacent the car track for moving the ejecting frame outward.

6. An apparatus of the class described embodying a car delivery device, said device including a horizontally movable ejecting member and means including a pivotally mounted sectional arm located adjacent the car track for operating the ejecting member.

7. An apparatus of the class described embodying a car delivery device, said device including a horizontally movable ejecting member, means including a pivotally mounted sectional arm located adjacent the car track for operating the ejecting member, and springs extending from opposite sides of the arm and disposed in opposite directions for returning the arm to normal position after the operation of the ejecting member.

In testimony whereof I affix my signature.
JOHN M. KERR.
